(57) **CLAIM**

The ornamental design for a license plate frame, as shown and described.

DESCRIPTION

FIG. 1 is an environmental perspective view of a license plate frame showing my new design;

FIG. 2 is an environmental front elevational view thereof;
FIG. 3 is a right side elevational view with the left side being a mirror image thereof; and,

FIG. 4 is a top plan view thereof with the bottom view being a mirror image thereof.

The broken line showing of the indicia on the license plate is for illustrative purposes only and forms no part of the claimed design.
